UNITED STATES PATENT OFFICE

126,636

DESIGN FOR A TURBINE AUXILIARY POWER PLANT

Nathan C. Price, Hollywood, Calif.

Application October 25, 1940, Serial No. 96,033

Term of patent 7 years

To all whom it may concern:

Be it known that I, Nathan C. Price, a citizen of the United States, residing at Hollywood, in the county of Los Angeles and State of California, have invented a new, original, and ornamental Design for Turbine Auxiliary Power Plants, of which the following is a specification, reference being had to the accompanying drawing, forming part thereof.

Figure 1 is a side perspective view of a turbine auxiliary power plant, showing my new design.

Figure 2 is a perspective view of the turbine auxiliary power plant of Figure 1 taken slightly above and to the left side of one end thereof.

Figure 3 is a perspective view of the turbine auxiliary power plant of Figure 1 taken slightly below and to the left side of the end opposite that shown in Figure 2.

Figure 4 is a perspective view of the turbine auxiliary power plant of Figure 1 taken above and to the left of the side opposite that shown in Figure 1.

I claim:

The ornamental design for a turbine auxiliary power plant, as shown.

NATHAN C. PRICE.
